UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,494, dated September 27, 1881.

Application filed August 9, 1881. Term of patent 3½ years.

To all whom it may concern:

Be it known that I, HENRY HORAN, of East Orange, in the county of Essex and State of New Jersey, have invented a new and original 5 Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is the central group of the carpet, representing a bouquet of star-flowers with rich

foliage surrounding it. The leaves may be 15 shaded similar to autumn leaves, giving to the design a rich and glowing appearance. The group A is surrounded by twigs and branches bearing leaves, which may be similarly shaded, some of said branches bearing flowers, as shown. 20

I claim—

The design for carpets, consisting of the figures A B, substantially as shown.

HENRY HORAN.
